HANDLE FOR AN ELECTRIC HAIR STYLER OR THE LIKE

Denis J. Jordan, Eau Claire, Wis., assignor to National Presto Industries, Inc., Eau Claire, Wis.

Filed Aug. 26, 1971, Ser. No. 175,425

Term of patent 14 years

Int. Cl. D28—03
U.S. Cl. D86—10 F

FIG. 1

FIG. 2

FIG. 3

FIG. 4

FIG. 5

FIG. 1 is a side elevational view of a handle for an electric hair styler or the like showing my new design, the opposite side thereof being a mirror image thereof;

FIG. 2 is a top plan view thereof;

FIG. 3 is a bottom plan view thereof;

FIG. 4 is a view of one end thereof; and

FIG. 5 is a view of its opposite end.

I claim:

The ornamental design for a handle for an electric hair styler or the like, substantially as shown and described.
